UNITED STATES PATENT OFFICE.

WILLIAM H. CARSON, OF NEW ROCKFORD, NORTH DAKOTA.

DESIGN FOR A STREET LAMP.

Application filed April 17, 1929. Serial No. 30,924. Term of patent 14 years.

To all whom it may concern:

Be it known that I, WILLIAM H. CARSON, a citizen of the United States, residing at New Rockford, in the county of Eddy and State of North Dakota, have invented a new, original, and ornamental Design for a Street Lamp, of which the following is a specification, reference being had to the accompanying drawings, forming part thereof, wherein:

Fig. 1 is a perspective view of a street lamp embodying my design;

Fig. 2 is a front elevation of the same; and
Fig. 3 is a side elevation of the same.

What is claimed is:

The ornamental design for a street lamp substantially as shown.

WILLIAM H. CARSON.
